(57) CLAIM

An ornamental design for a sports bra as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a sports bra, embodying my new design shown flat on a surface;

FIG. 2 is a front view of the sports bra of FIG. 1, shown as modeled by a manikin;

FIG. 3 is a left side view of the sports bra of FIG. 1, shown flat on a surface;

FIG. 4 is a left side view of the sports bra of FIG. 1, shown as modeled by a manikin;

FIG. 5 is a right side view of the sports bra of FIG. 1, shown flat on a surface;

FIG. 6 is a right side view of the sports bra of FIG. 1, shown as modeled by a manikin;

FIG. 7 is a rear view of the sports bra of FIG. 1, shown flat on a surface;

FIG. 8 is a rear view of the sports bra of FIG. 1, shown as modeled by a manikin; and,

FIG. 9 is a rear view of the sports bra of FIG. 1, shown flat on a surface with the bra straps folded under the bra to reveal the inner surface.

In this application, the “winged logo decoration” appearing in FIGS. 1, 2, 7 and 9 forms no part of the claimed ornamental design, nor does the manikin appearing in FIGS. 2, 4, 6, and 8. The color shown on the claimed design forms no part thereof.
